To all whom it may concern:

Be it known that I, WILLIAM H. The figure is a perspective view of a magazine mail box, right side up, in operative position, with its trough-shaped and for-wardly sloping cover uppermost, with its front in the foreground, and with its supporting brackets and the hinges for the rear edge of said cover at the rear of said perspective view, the rear straight side of the box being higher than its front, showing my new design.

I claim:

The ornamental design for a magazine mail box, as shown and described.
